2 Claims. (Cl. 170—159)

This invention relates to fluid propulsion and in particular provides a propeller having particular utility, when driven mechanically against the resistance of a fluid, in the propulsion of vessels through such fluid or for projecting a blast of such fluid. This invention in particular provides an efficient propeller which is particular provides an efficient propeller which is particularly characterized by the fact that it requires a much smaller diameter than is required with conventional screw propellers to accomplish the same thrust, and which is further characterized by high efficiency in conversion of torque to thrust.

It is believed that the high efficiency and smaller diameter requirement of the propeller of this invention is at least in part the result of a unique manner of combining the streams of fluid gathered by each blade into a single united, ejected stream having an area substantially less than the sum of stream areas upon which the blades initially act.

Broadly speaking, the propeller of this invention includes a pair of blades having obtuse angled, semi-conic surfaces mounted together at their apices on a shaft with one blade disposed on each side of the shaft with its conic axis tilted rearwardly and outwardly from the conic axis of the other, such that the pair of semi-conic blade surfaces provide leading edges perpendicular to the axis of the shaft and aligned with each other on opposite sides of the shaft, and such that the trailing edge of each blade leads into the center of the other blade and is approximately coincident with the conic axis of the other blade.

With this manner of construction in a marine propeller, as the propeller is rotated to advance the leading edges of the two blades, a stream of water is scooped up by each blade and united with the stream of water gathered by the other blade and ejected producing a rearward thrust.

For a more complete understanding of this invention reference is made in the appended drawing in which:

Fig. 1 is an end view of a propeller constructed in accordance with the principles of this invention showing the trailing and leading edges of the blades lying in a plane revolved 30° counterclockwise from the vertical;

Fig. 2 is a side elevation of the propeller shown in Fig. 1 having the blades in the same position as shown in Fig. 1;

Fig. 3 is an elevational view of the same propeller shown in Figs. 1 and 2 with the trailing and leading edges of the blades lying in a horizontal plane, that is, the propeller has been revolved 120° in its normal di-

2

rection of rotation (clockwise in Fig. 1 from the position shown in Fig. 2; and

Fig. 4 is a view of the propeller shown in Figs. 1-3 revolved 30° in the normal direction of rotation from the position shown in Figs. 1 and 2 and with the nearer blade removed.

In the drawings the reference numeral 10 generally designates a propeller constructed in accordance with this invention, including a pair of identical blades 11 and 12 mounted on the stub 13 of a drive shaft 14. Each blade 11 and 12 is a half surface of a cone having an apex angle of 120° cut off by a plane perpendicular to the axis of the cone.

Referring more particularly to blade 11, conic blade 11 is provided with a straight leading edge 15 which, at its inner end, intersects the inner end of a straight trailing edge 16, the length of which is identical with that of leading edge 15. The angle of intersection of edges 15 and 16 is 120°. The outer ends of leading and trailing edges 15 and 16 lie at opposite ends of semicircular outer edge 17 which lies in a plane perpendicular to the plane determined by intersecting edges 15 and 16.

Blade 11, thus enclosed between edges 15, 16 and 17 is half of a 120° conic surface with its apex at the point of intersection of edges 15 and 16, affixed in stub 13. Leading edge 15 and trailing edge 16 lie in a plane which coincides with the axis of rotation of shaft 14, leading edge 15 lying at an angle of 90° to the axis of rotation and trailing edge 16 lying at an angle of 30° to such axis of rotation.

Blade 12 has the identical shape of blade 11, and has a leading edge 18, a trailing edge 19 and an outer edge 20 which define between them half of a 120° conic surface similarly affixed at its apex in stub 13, but disposed on the opposite side of shaft 14 from blade 11. Leading edge 18 and trailing edge 19 also lie in the same plane as edges 15 and 16 of blade 11, but edge 18 is disposed on the opposite side of the axis of rotation from edge 15, and similarly edge 19 is disposed on the same side of the axis of rotation as edge 15, but opposite corresponding trailing edge 16.

It will be observed, because of the angles in the particular 120° semi-conic surfaces illustrated, trailing edge 19 coincides with the axis of the conic surface forming blade 11, and similarly edge 16 coincides with the conic axis of blade 12. The adjacent pairs of these edges are separated by equal (60°) angles. This represents the preferred form of construction for obtaining maximum efficiency. It is, however, possible within the scope of this invention to employ blades defining semi-conic surfaces having greater or lesser obtuse apex angles, the important feature of the invention being the employment of a pair of opposing semi-conic blade surfaces which gather fluid from two cutting areas on opposite sides of the shaft and throw the two resulting streams of fluid into a single stream in a direction aligned with the axis of rotation and having a transverse area substantially less than the sum of the cutting areas. Thus, in effect, the pair of blades cooperate together in acting upon the water or other fluid, to thrust the fluid from the propeller as a single, united, stream.

We claim:

1. A propeller which comprises a shaft rotatable

about a central axis and a pair of identical blades, each formed to define a semi-conic surface having an obtuse apex angle, said blades being affixed to said shaft at their apices and lying on opposite sides of said shaft with their leading edges aligned on opposite sides of said shaft perpendicular to the axis of rotation of said shaft and with their trailing edges extending from said shaft in the plane determined by said axis of rotation and the line of said leading edges.

2. A propeller according to claim 1 in which the apex angle of each said half-cone blade is 120°.

CERTIFICATION OF CORRECTION

Patent No. 2,954,083

September 27, 1960

Olav A. Skarsten et al.

It is hereby certified that error appears in the above numbered patent requiring correction and that the said Letters Patent should read as corrected below.

Column 1, lines 20 and 21, strike out "which is particula provides an efficient propeller"; line 53, for "made in" read -- made to --; column 2, line 1, for "Fig. 1" read -- Fig. 1) --; column 4, line 8, list of references cited, under "FOREIGN PATENTS", for the patent number "20,782" read -- 20,783 --.

Signed and sealed this 6th day of June 1961.
